[57] CLAIM

The ornamental design for a combined electronic computer and video telephone, as shown and described.

DESCRIPTION

FIG. 1 is a top, front and right side perspective view of a combined electronic computer and video telephone showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a top, rear and left side perspective view thereof showing the keyboard and display panel in closed position; and

FIG. 9 is an exploded top, front and left side perspective view thereof showing the telephone handset in separated position.
